UNITED STATES PATENT OFFICE.

ARCHIE J. WILLIAMS, OF COVINGTON, KENTUCKY.

WIRELESS SOUNDER.

1,220,920.

Specification of Letters Patent. Patented Mar. 27, 1917.

Application filed May 21, 1915. Serial No. 29,543.

To all whom it may concern:

Be it known that I, ARCHIE J. WILLIAMS, a citizen of the United States, residing at Covington, in the county of Kenton and State of Kentucky, have invented certain new and useful Improvements in Wireless Sounders; and I do hereby declare the following to be a full, clear, and exact description of the invention, such as will enable others skilled in the art to which it appertains to make and use the same.

This invention relates to new and useful improvements in wireless sounders, and has for its principal object to provide a sounder wherein the magnets are adjustable with relation to the diaphragms.

Another object of the invention is to provide a sounder in which a delicate adjustment may be easily and quickly made.

20 A further object of the invention is to provide a sounder which will remain stationary with the remainder of the instruments, thus doing away with the necessity of using a head receiver and the like.

25 Still another object of the invention is to provide a device which may be used for receiving over long distances for operating through interfering stations, and to provide a device which may be tuned for close work.

30 With these and other objects in view, the invention consists in the novel combination and arrangement of parts which will be fully set forth in the following specification and accompanying drawings, in which,

35 Figure 1 is a front view in elevation of a sounder constructed in accordance with this invention.

Fig. 2 is a horizontal sectional view taken on line 2—2 of Fig. 1,

40 Fig. 3 is a vertical sectional view through the center of Fig. 1,

Fig. 4 is a front view in elevation of the sounder showing the diaphragm removed,

Fig. 5 is a horizontal sectional view taken 45 on line 5—5 of Fig. 4, and

Fig. 6 is a wiring diagram of the device.

Referring to the drawings by characters of reference, the numeral 1 designates as an entirety the sounder comprising a casing 50 which is formed of the bottom 2, having extending upwardly therefrom the rear wall 3. Suitable side walls 4 are secured to the bottom and to the rear wall and the upper edges of these side walls are connected by

55 the top 5. Formed centrally of the rear wall

is a suitable opening 6 for the reception of the internally screw threaded sleeve 7, the use of which will appear as the description proceeds. A suitable frame designated generally by the numeral 8, comprising the top, bottom, and sides 9, 10, and 11, respectively, is secured to the front edges of the top and side walls, and the lower edge of this frame rests on the base as clearly shown in Fig. 3. A suitable groove 12 is formed in each of the members 9, 10, and 11 forming the frame 8 and the diaphragm 13 is held in place by the walls of the groove 12. A suitable bracket 14 comprising the vertical portion 15, having formed at its upper end the horizontal arm 16, is secured to the rear wall 3, and the horizontal arm terminates at its outer end in the vertically extending sleeve or loop 17 which acts as a guide for the magnet-adjusting stem which will be more fully hereinafter described. Coöoperating with the bracket 14 in holding the magnets is a suitable transversely extending bar 18 which is secured to the side walls and extends entirely across the casing 1 near the 80 open ends thereof.

The magnets, designated generally by the numeral 19, comprise the cores 20 of steel or a similar easily excited metal, which cores are supported on the bar 21 having formed centrally a collar 22 by means of which the adjusting stem is connected thereto. Surrounding each of the cores 20 is a suitable coil of magnet wire 23 which may be wound to any suitable resistance, but in the present 90 device, as illustrated, these magnets are wound to a resistance of three thousand ohms.

Swivelly connected to the collar 22 of the bar 21 is the adjusting stem 24 which is 95 screw threaded as at 25 and provided at its opposite end with the head 26 which is preferably knurled or milled to provide a finger grip. The threads 25 are arranged to engage the threads on the inner side of the 100 sleeve 7 and surrounding the sleeve and bearing against the head and the rear wall 3 of the casing 1 is a suitable coil spring 27. This coil spring is arranged to frictionally engage the head 26 and the rear wall 3 to 105 hold the head against accidental turning. The magnets 23 are supported on the bar 18, while the adjusting stem 24 is supported in the bracket 17 and in the sleeve 7. Both the magnets and the adjusting stem are ar- 110

ranged to move toward and away from the diaphragm as the stem is turned. Mounted in the lower portion of the casing 1 is a suitable condenser designated generally by 5 the numeral 28, and this condenser bridges the channels of the magnets as clearly illustrated in the diagrammatic view in Fig. 6. In order to connect the device in circuit with the remaining instruments, there are 10 provided the binding posts A and B, and each binding post in each set is given a designation for the sake of clearness in the description. The binding post designated by the numeral 29 in the set A is connected by 15 means of the wire 30 to one terminal of the magnet, while the opposite terminal of the magnet is connected by means of the wire 31 to the binding post 32 of the set A. Connected to the binding post 29 is a suitable 20 wire 33, the opposite terminal of which is connected to the binding post 34 in set B, and connected to this binding post 34 is the wire 35, the opposite terminal of which is connected to one terminal of the condenser 25 28 as at 36. The opposite terminal 37 of the condenser is connected by means of the wire 38 to the binding post 39 in set B, and this binding post is connected by means of the wire 40 to the binding post 32. It will 30 thus be seen that regardless of which set of binding posts is used, the current will flow through the magnets and the condenser will bridge the terminals of the magnets.

It will be apparent from the foregoing 35 that in use various adjustments of the magnets with relation to the diaphragm may be made by turning the thumb screw 26. This will cause the magnets to move toward or be moved away from the diaphragm, and in view of the fact that it is a screw adjustment, it will be evident that very delicate adjustments may be made. It is also evident that due to the frictional contact of the spring 27 against the thumb screw 26, 40 danger of the magnets being accidentally moved either toward or away from the diaphragm and the destroying of the adjustments is eliminated.

While in the foregoing there has been 45 shown and described the preferred embodiment of this invention, it is to be understood that such changes may be made in the combination and arrangement of parts as

will fall within the spirit and scope of the invention as claimed.

What is claimed is:

1. A wireless receiving apparatus including a casing, a diaphragm forming the front wall of said casing, the rear wall of said casing being centrally apertured, an internally threaded sleeve seated in said aperture, a stem threaded through said sleeve, a thumb piece at the outer end of said stem, a head at the inner end of the stem, magnets within the casing, the said head being swivelly connected to the magnets whereby upon turning of the thumb piece the magnets may be adjusted toward or away from the diaphragm and a horizontal supporting bar extending transversely of the casing beneath the magnets for holding said magnets in proper position.

2. A wireless telegraph apparatus comprising a casing, a diaphragm forming the front wall of said casing, the rear wall of said casing being provided with a central opening, a sleeve having internal screw threads extending through said openings, a stem threaded through the sleeve, a thumb piece at the outer end of said stem, a compression coil spring surrounding the stem and the outwardly projecting portion of the sleeve, said spring biting against the thumb piece and the outer side of the rear wall of the casing to hold the stem in various adjusted positions, a head at the inner end of the stem, a pair of magnets within the casing, the head being swivelly connected to the magnets whereby upon turning of the stem the magnets will be moved toward or away from the diaphragm, a horizontal supporting bar extending transversely through the casing in the rear of the diaphragm for providing a supporting means for the magnets throughout their length of travel, a bracket attached to the inner side of the rear wall of the casing and a pair of upwardly extending arcuate arms partially embracing the stem and forming a support for the inner end thereof.

In testimony whereof I affix my signature in presence of two witnesses.

ARCHIE J. WILLIAMS.
